Melvin A. Bard and Ia Lene Bard,
Mountain View, Calif.

Application November 8, 1952, Serial No. 22,211

Term of patent 14 years

(Cl. D58—11)

To all whom it may concern:

Be it known that I, Melvin A. Bard, a citizen of the United States of America, resident of Mountain View, California, and I, Ia Lene Bard, a citizen of the United States of America, resident of Mountain View, California, have invented a new, original, and ornamental Design for a Hat Box of which the following is a specification, reference being made to the accompanying drawing, forming a part thereof:

Fig. 1 is a side elevational view of a hat box showing our new design.

Fig. 2 is a fragmentary top plan view; and

Fig. 3 is a cross sectional view taken on the line 3—3 of Fig. 1.

The sides not shown are the same as the side shown.

We claim:

The ornamental design for a hat box, substantially as shown and described.

MELVIN A. BARD.
IA LENE BARD.
